(57) **CLAIM**

The ornamental design for a two-piece keychain, substantially as shown and described.

DESCRIPTION

FIG. 1 is an elevational a plan view of the two-piece keychain.

FIG. 2 is an elevational view of the two-piece keychain of FIG. 1, rotated by 90 degrees.

FIG. 3 is an elevational view of the two-piece keychain of FIG. 1, rotated by 180 degrees.

FIG. 4 is an elevational view of the two-piece keychain of FIG. 1, rotated by 270 degrees.

FIG. 5 is an elevational view of the two-piece keychain of FIG. 1, with the second piece rotated by 90 degrees relative to the first piece.

FIG. 6 is a first end view of the two-piece keychain of FIG. 1

FIG. 7 is a second end view of the two-piece keychain of FIG. 1.

FIG. 8 is a perspective view of the two-piece keychain of FIG. 1, showing the first and second piece separated from each other.

FIG. 9 is an inside end view of the first piece shown in FIG. 8.

FIG. 10 is an inside end view of the second piece shown in FIG. 8.

FIG. 11 is an elevational view of the first piece only; and, FIG. 12 is an elevational view of the second piece only.

The attached key rings (FIGS. 1-12) and the circular end features (FIGS. 6 and 7) shown with dotted lines are for illustrating the environmental structure, and form no part of the claimed design.

1 Claim, 4 Drawing Sheets
